(57) **CLAIM**

The ornamental design for a roll up shoe and leg protector, as shown and described.

DESCRIPTION

FIG. 1 is perspective view of a roll up shoe and leg protector showing my new design;

FIG. 2 is a right side elevational view thereof;

FIG. 3 is a top plan view thereof;

FIG. 4 is a left side elevational view thereof; and,

FIG. 5 is a bottom plan view thereof.

The dashed lines in FIGS. 2 and 4 represent a leg and shoe of a wearer utilizing the present invention, and in no way form a part of the present design.
